UNITED STATES PATENT OFFICE.

FRANCIS HILDRETH, OF CLERMONT, NEW JERSEY.

THILL-COUPING.

SPECIFICATION forming part of Letters Patent No. 390,019, dated September 25, 1881

Application filed March 16, 1888. Serial No. 267,380. (No model.)

To all whom it may concern:

Be it known that I, FRANCIS HILDRETH, a citizen of the United States, residing at Clermont, in the county of Cape May and State of New Jersey, have invented a new and useful Improvement in Thill-Couplings, of which the following is a specification.

My invention relates to improvements in thill-couplings; and it has for its object to provide means whereby the wear may be taken up to prevent rattling, and, furthermore, to provide means whereby the thills may be readily attached and detached.

With these objects in view the invention consists in a certain novel construction and arrangement of devices, fully set forth hereinafter, and specifically pointed out in connection with the accompanying drawings, wherein—

Figure 1 is a side view. Fig. 2 is a longitudinal sectional view. Fig. 3 is a bottom plan view. Fig. 4 is a transverse section through the pivot, with the rubber block omitted.

Referring by letter to the drawings, A designates the axle, under which is arranged the clip-plate B, having the apertures C C therein, through which pass the lower ends of the arms of the clip D. The clip-plate is provided with the forward extension, d, which is rounded on its under side at the front end, and provided on the upper side with the vertical ears F F, having the vertical slots G G in their upper ends. The rounded portion of the clip-plate comprises a cam, which will be more fully described hereinafter.

H represents the thill-iron, which is provided with the rigid pivot I, having its ends mounted in the slots in the upper ends of the ears F.

K represents a loop-shaped clamp or clevis having its parallel arms k k mounted at their upper ends on the laterally-extending ends of the pivot I. This clamp or clevis swings under the rounded end of the clip-plate, and it is provided at the center of its lower end with the thumb-screw I₁, which is mounted in a tapped aperture, l, and bears in a groove, M, which is formed in the rounded face of the clip-plate. This screw may bear against the

lower side of the clip directly; but the groove

is formed therein for the reason that its ends form stops against which the end of the thumb-screw strikes to limit the swing of the clamp or clevis. The advantage of this is that if the thumb-screw jars loose while the vehicle is in motion the clamp or clevis cannot swing clear of the end of the clip-plate and thus allow the ends of the pivot to become dismounted from the bearings.

It will be observed that as the lower end of the clamp or clevis swings rearwardly the pivot I is drawn downward in the slots, and therefore, as the bearings wear, the pivot may be adjusted to prevent looseness.

The web of the thumb-screw is provided with the notches N N; and O represents a coiled spring, which is attached at its rear end to the under side of the clip-plate, and is provided at its front end with a loop, P, which engages one of the notches in the thumb-screw. This spring holds the thumb-screw from turning or jarring loose, and thus prevents all displacement of the parts of the coupling.

A block of rubber, R, is attached to the upper side of the clip-plate between the ears, and when the pivot I is drawn down in the slots G by the clamp or clevis the under side of the bearing at the rear end of the thill-iron bears on its upper side and all rattling is avoided.

It will be observed that the invention is simple, the thill is easily attached and detached, the bearings are adjustable to take up wear and the parts are so connected that there is no possibility of a displacement.

If desired, the thill-iron may be mounted loosely on the transverse pivot, but the rigid pivot herein described is considered preferable; also, the rubber block may be omitted, and the ends of the pivot may bear in the lower ends of the slots G; but I prefer to use the rubber block, as it renders the adjustment easier, and obviates the necessity of frequent adjustment.

Having thus described my invention, I claim—

1. In a thill-coupling, the combination of the clip-plate having ears on its upper side provided with bearings, the thill-iron having a pivot mounted in the bearings, the clamp or clevis attached to the pivot and passing under the clip-plate, the thumb-screw mounted in the

lower end of the clamp or clevis and having notches N therein, and the spring O, having a loop to engage one of the said notches to hold the thumb-screw from turning or jarring loose, 5 substantially as specified.

2. In a thill-coupling, the combination of the clamp or clevis engaging the thill-iron so as to hold it in position, the thumb-screw to lock the clamp or clevis, and the spring O, to engage to the thumb screw, as set forth.

In testimony that I claim the foregoing as my own I have hereto affixed my signature in presence of two witnesses.

FRANCIS HILDRETH.
